UNITED STATES PATENT OFFICE.

BENJAMIN DOUGLAS THOMAS, OF ITHACA, NEW YORK, ASSIGNOR OF ONE-TENTH TO THOMAS-MORSE AIRCRAFT CORPORATION, OF ITHACA, NEW YORK, A CORPORATION OF NEW YORK.

AIRPLANE RADIATOR.

Application filed June 1, 1922. Serial No. 565,196.

To all whom it may concern:

Be it known that I, BENJAMIN DOUGLAS THOMAS, a subject of the King of Great Britain, and a resident of Ithaca, in the county of Tompkins and State of New York, have invented a certain new and useful Improvement in Airplane Radiators, of which improvement the following is a specification.

This invention relates to radiators for airplane engines, and has for its object to reduce the resistance to a minimum and to obtain a maximum radiating efficiency with the least possible weight.

In general terms, my invention may be said to comprise a radiator formed with a body having an exterior contour of substantially, or approximately a streamline form with an interior longitudinal passage having an opening at the front end for the admission of air, and tubes or air passages extending laterally from said interior passage through the water space and discharging through the outside wall for permitting a rapid flow of air from the central passage outward. Another feature of my improvement comprises an oil tank or chamber in combination with the radiator for completing the general streamline form of the body.

Various forms of construction, embodying, in general, a body of approximately a streamline design with an interior longitudinal air passage and lateral tubes or air passages, may be employed, and I have illustrated one such construction in the accompanying drawings, in which Figure 1 is a plan; Fig. 2, a side elevation; Fig. 3, a transverse section taken substantially on the line 3—3 of Figs. 1 and 5; Fig. 4, a front elevation; and, Fig. 5, a central horizontal section, taken on the line 5—5 of Fig. 2.

According to my improvement, the exterior walls of the body and also the walls of the interior passage may be of any suitable construction and have any suitable or preferred connection with the lateral air passages, but according to the particular construction shown in the drawings, the streamline body is formed in two similar halves, each comprising a vertically curved section, as indicated in Figs. 3 and 4, and fastened together side by side along its length top and bottom. The interior longitudinal passage is thus formed of a substantially elliptical section and is preferably

made converging from the front toward the rear, as shown. The radiator is preferably constructed with the tubes, 6, of the type in which the ends are hexagonal and soldered together, in which case, the outer walls, 7, of the body and the interior walls, 8, of the central longitudinal passage, are composed of said soldered hexagonal ends of the tubes. The tubes or air passages 6, are preferably inclined diagonally from the front toward the rear.

The top portion of the body comprises two water inlet chambers or headers, 9, 9, one for each half section of the radiator, and communicating with the water space around the tubes, 6. At the bottom of the body are located the two corresponding headers or chambers, 10, 10, for the forward flow of the water, after passing downward around the tubes, to the water legs, 11, 11, at the front end of the body, through which the water passes to the outlet pipe connections, 13, at the top of the body. This circulation of the cooling water from the inlet pipe connections, 12, through the upper chambers, 9, downward around the tubes, 6, forward through the lower chambers or headers, 10, and upward through water legs, 11, to the outlet connections, 13, is clearly indicated by the arrows in Figs. 1, 2, 3 and 4 of the drawings.

As the radiator moves through the air in the forward flight of the airplane, air enters the front open end of the central interior passage, and then flows in large volume laterally out through the tubes, 6, to either side of the body, this flow being accelerated by the partial vacuum or suction at either side induced by the rush of air along the outer sides of the body, all as indicated by the arrows in Fig. 5 of the drawing. This greatly increases the effectiveness of the radiation.

In order to complete the streamline form at the rear of the radiator there may be added a tank or reservoir, 15, which may be used to hold a supply of oil, or other liquid, and the central interior passage of the radiator may be continued through this tank to the rear end, as indicated at 14, Fig. 5. This passage may also communicate with the exterior by the lateral passages, 21. The portion of the air which continues on through the passage, 14, and through lateral

passages, 21, also serves to cool the oil in tank, 15. This tank may be provided with suitable inlet and outlet pipe connections, 18 and 19. The radiator body may be supported in any convenient or preferred manner upon the air plane by suitable lugs, 20, indicated in Fig. 1.

The flow of air through the interior passage may be controlled by suitable shutters, 10 and for this purpose, I have shown the elliptical shutter, 16, mounted on a vertical axis at the front opening of said passage. There is also shown a similar shutter mounted in the passage, 14, at the forward end of the 15 tank, 15. These shutters may be operated either independently or simultaneously by suitable means, and be adjusted to suit different conditions. In cold weather the forward shutter may be closed, and the rear one 20 opened, which would tend to rapidly warm up the oil as well as the cooling water. This combination of radiator and oil tank has the particular advantage that the heat of both the radiator water and the oil may 25 be maintained under conditions of low throttle and gliding of the airplane, at which times there is normally a great tendency for the water and oil to cool rapidly. By this combination, the time required for warming 30 up the motor, preparatory to starting in cold weather, may also be diminished. When it is desired to increase the cooling of the water and diminish the cooling of the oil, the forward shutter may be left open, 35 and the rear shutter closed.

It will also be apparent that the cooling effectiveness of the radiator may be increased by spreading the two halves farther apart at the front end, thereby allowing a greater 40 volume of air to enter the central interior passage, and this at the same time, increases the suction at each side, thereby causing an increased flow through the radiating tubes. By this means, it is possible to adapt one 45 radiator to a variety of different engines, and provide for different temperatures and climates in different parts of the country.

Having now described my invention, what I claim as new and desired to secure 50 by Letters Patent is:

1. An airplane radiator comprising a body of approximately streamline form provided with a central longitudinal air passage, and honeycombed water radiator sections 55 surrounding said air passage with lateral air ducts extending from the central air passage to the exterior and inclined rearwardly.

2. An airplane radiator comprising a body 60 of approximately streamline form provided with a central longitudinal air passage, water cooling sections surrounding said passage, and lateral air ducts leading from said passage to the outside.

3. An airplane radiator comprising a body 65

of approximately streamline form provided with a central longitudinal air passage, water cooling sections surrounding said passage, lateral air ducts leading from said passage to the outside and an adjustable shutter 70 at the front of said passage.

4. An airplane radiator comprising a body of approximately streamline form provided with a central longitudinal air passage, water cooling sections surrounding said passage, 75 two sets of air tubes leading in opposite directions from said passage thro said water sections to the outside, and water chambers connected to said sections.

5. An airplane radiator comprising a body 80 of approximately streamline form provided with a central longitudinal air passage, water cooling sections surrounding said passage, two sets of air tubes leading in opposite directions from said passage thro said 85 water sections to the outside, inlet water chambers at the top and communicating with the water space around said tubes, and other water chambers at the bottom.

6. An airplane radiator comprising a body 90 of approximately streamline form provided with a central longitudinal air passage, water cooling sections surrounding said passage, two sets of air tubes leading in opposite directions from said passage thro said 95 water sections to the outside, inlet water chambers at the top and communicating with the water space around said tubes, water legs on either side of the inlet of said passage, and water chambers at the bottom 100 for the forward flow of water to said legs.

7. An airplane radiator comprising a body 105 of approximately streamline form provided with a central longitudinal air passage converging towards the rear, honeycomb water sections surrounding said passage, and lateral air ducts leading from said passage through said sections.

8. An airplane radiator comprising a body 110 of approximately streamline form provided with a central longitudinal air passage of substantially elliptical section, honeycomb water sections surrounding said passage, and lateral air ducts leading from said passage through said sections.

9. An airplane radiator comprising a body 115 of approximately streamline form comprising two similar curved half sections connected together longitudinally at top and bottom with a central longitudinal air passage converging towards the rear and water radiator sections surrounding said air passage with lateral air ducts extending from the central air passage to the exterior and inclined rearwardly.

10. A combined radiator and oil tank for 120 airplanes, comprising a body of approximately streamline form with the radiator at the forward portion and the tank at the rear portion, said body having a central 125 130

longitudinal air passage extending through both radiator and tank, and lateral air passages for the radiator.

11. A combined radiator and tank for air-
5 planes, comprising a body of approximately streamline form with a radiator at the front portion and a tank at the rear, and having a central longitudinal air passage extending through both radiator and tank, lateral tubes
10 for the radiator leading from the central passage through the water space to the outside wall and adjustable shutter at the front opening of the air passage and another

shutter in the passage at the forward end of the tank.

12. A combined radiator and oil tank for air planes, comprising a body of approxi-
15 mately streamline form with the radiator at the forward portion and the tank at the rear portion, said body having a central longi-
tudinal air passage extending through both radiator and tank, and lateral air passages for both radiator and tank.

In testimony whereof I have hereunto set my hand.

BENJAMIN DOUGLAS THOMAS.
